POWER SHOVEL

Application filed April 16, 1926. Serial No. 102,397.

This invention relates to improvements in power shovels, and more particularly to those of the internal combustion engine operated type wherein the shipper shaft is chain driven 5 from what is termed the "digging shaft" mounted near the forward end of the revolving platform or turntable of the machine.

Difficulty has been encountered in raising and lowering the boom on these machines, 10 due to the fact that it interferes with the tension of the driving chain previously mentioned, the pivotal axis of the boom being below and in advance of the axis of the digging shaft so that the distance between the 15 latter and the shipper shaft varies with adjustment of the boom.

One object of the invention, therefore, is to provide compensating means in conjunction with the boom and chain for automatically 20 regulating the tension of the latter throughout various adjustments of the boom.

Another object resides in the provision of improved brace rods for the boom including the provision of means for absorbing the 25 shocks incident to the side swipes or thrusts encountered by the dipper stick.

Other objects and advantages will become apparent from the following description taken in connection with the accompanying 30 drawings wherein one form of the invention is illustrated.

Figure 1 is a slide elevational view of the front and of a power shovel, showing the improved tension means applied thereto;

Fig. 2 is an enlarged plan view of Fig. 1, some of the parts being removed;

Fig. 3 is a side elevation of Fig. 2;

Fig. 4 is an enlarged section on line 4-4 of Fig. 1;

Fig. 5 is an enlarged section on line 5-5 of Fig. 3;

Fig. 6 is a section on line 6-6 of Fig. 5; and

Fig. 7 is a bottom plan view of one of the parts in Fig. 5.

Referring more particularly to the drawings and first to Figs. 1, 2 and 3 thereof, a dipper stick 1 provided at its outer end with a shovel 2 of any suitable construction is mounted upon a boom 3, the latter being pivotally attached to the forward end of the re-

volving platform or turntable 22. The so-called crowding action or back and forth movement is imparted to the dipper stick by mechanism of well-known construction which comprises, in general, the sprocket wheel 5 mounted on the digging shaft 4, the sprocket wheel 6 fixed upon the shipper shaft 7 and connected to sprocket wheel 5 by means of a sprocket chain 8, and suitable pinions (not shown) which are fixed on shipper shaft 7 and engage racks 9 on the underside of the dipper stick.

As previously explained and from the arrangement of parts just described, it will be apparent that upon pivotal adjustment of the boom 3 the distance between the shipper shaft and the digging shaft will be varied.

Thus, it will be apparent that the drive or sprocket chain if passed directly between sprocket wheels 5 and 6 would be extremely 70 taut when the boom was in its lowermost position of adjustment, while any adjustment from such point upwardly would result in slack in the chain. To provide against this difficulty the present invention, as above

pointed out, contemplates the provision of means for automatically regulating or controlling the tension of the chain upon adjustment of the boom, this means being so constructed and arranged as to maintain the 75 chain tension at substantially a constant value.

To this end, the invention contemplates, in the form thereof illustrated in the drawings, the provision of triangularly-shaped members 10 and 11 arranged on either 80 side of boom 3 and pivotally connected thereto by means of a pin 12 extending through the boom and the forward ends of these members.

A sprocket wheel 13 is arranged between members 10 and 11 and is held in operative or 85 assembled relation with respect thereto by means of a pin 14 passing loosely through this sprocket wheel and having its ends mounted in members 10 and 11 and held

therein by means of pins 15. A second 90 sprocket wheel 16 similar to sprocket wheel 13 is arranged between the rear ends of members 10 and 11 and held in assembled relation with respect thereto by means of a pin 17

similar to pin 14. A frame 18 comprising a 95

100

base 19 and upwardly extending spaced arms 20 and 21, is secured to the revolvable frame or platform 22 of the machine by means of bolts 23, arms 20 and 21 embracing members 10 and 11 and being connected thereto by means of bolts 24 and 25 or the like provided with heads 26 and 27 arranged for sliding movement in slots or grooves 28 formed in members 10 and 11.

The operation of the improved tensioning or equalizing device is as follows: Upon elevation of boom 3, for example, through an angle of about 30 degrees from the full-line position thereof shown in Fig. 3, the heads 26 and 27 of bolts 24 and 25, respectively, will coact with the grooves 28 in members 10 and 11 to cause pivotal movement of the latter in a counter-clockwise direction with respect to the boom about pin 12 as a center, so that sprocket wheels 13 and 16 and chain 8 trained thereabout assume the dotted line position shown, the contour and position of the slots or grooves 28 being such as to cause just the right amount of pivotal movement of members 10 and 11 with respect to the boom to take up on the chain an amount equal to the play or looseness which would otherwise result upon this elevation or adjustment of the boom due to the fact that the arcuate path of shipper shaft 7 about the pivot pin 3^a connecting the lower end of the boom to frame 22 is eccentric to and below the axis of rotation of digging shaft 4. The contour and position of the grooves or slots 28 is such that upon lowering of the boom bolt heads 26 and 27, which are relatively fixed, act to cause pivotal movement of members 10 and 11 in a clockwise direction with respect to boom 3 about pin 12 as a center, whereby more of the crowding chain is made available to compensate for the increase in the distance between the respective axes of rotation of shipper shaft 7 and digging shaft 4.

For the purpose of providing for wear in chain 8, members 10 and 11 may be provided with registering openings 29 and 30 at either side of pin 17, to permit of adjustment of the latter and sprocket wheel 16 in either direction.

Frame 18 may be cast in one piece and then split at 31 to facilitate assembly of the various parts.

From the foregoing it will be seen that improved means have been provided to automatically take up on the crowding chain 8 upon raising of the boom in such manner that the tension in the chain is substantially constant, the improved tensioning or equalizing means acting in the reverse manner upon lowering of the boom.

The boom 3 is provided at each side thereof with brace rods 32 connected to the boom at their upper ends by means of a bolt 33 and threaded at their lower ends to receive nuts 34, rods 32 being provided with the usual

turnbuckles, as shown. A hollow cylindrical member 35 is fitted over the lower end of each rod and provided with spaced apertured lugs 36 which receive a bolt 37 whereby member 35 is pivotally connected to the front end of frame 22, bolt 37 passing through a suitable lug 38 with which the frame may be provided. A spring 39 is arranged upon each rod 32 and is compressed between nut 34 and a cap 40 loosely fitting the rod and closing the open end of member 35. The cap 40 is provided with inwardly extending, diametrically arranged flanges 41 spaced laterally from the cap body and adapted to fit between similarly outwardly extending flanges 42 with which member 35 is provided at its open end, the arrangement being such that when cap 40 is fitted upon member 35 and given a quarter turn, the cap will be locked in position, as more clearly shown in Fig. 5. Member 35 and cap 40 may be provided with apertured lugs 43 and 44, respectively, the lugs being arranged to register when the cap is in locking position and receiving a bolt 45 for holding the cap in this position. By means of the construction just described, springs 39 provide a cushion to relieve the boom, dipper stick, the shipper shaft and the various other parts from the sudden shock which would otherwise occur due to side swiping with the dipper, or accidental engagement with an obstruction, the springs being of equal tension and acting normally to hold the boom in alignment with the longitudinal center line of the revolving platform.

The brace rods 32 and the cushion means or springs 39 associated therewith have been shown applied to the boom of a power shovel, but of course they may be used with equal effect for bracing the booms or like members of hoisting mechanism of other types.

While a definite embodiment of the invention has been shown and described, it will be understood, of course, that various changes may be made in the size, shape and arrangement of the parts without departing from the spirit of the invention or the scope of the claims.

The invention claimed is:

1. In a machine of the character described, the combination with a supporting frame, a driving shaft rotatably mounted on said frame, a boom connected to said frame for pivotal movement about an axis eccentric to the axis of rotation of said shaft, a shaft carried by said boom, and a flexible driving element connecting said shafts and traveling in a plane at right angles to the axes of the shafts, of means associated with said element and in its plane of travel and coacting therewith for automatically compensating for changes in the relative positions of said shafts upon said movement of the boom whereby the tension in said element is maintained substantially constant through the en-

tire range of movement of the boom with respect to the frame.

2. In a machine of the character described, the combination with a supporting frame, a driving shaft rotatably mounted on said frame, a boom connected to said frame for pivotal movement about an axis eccentric to the axis of rotation of said shaft, a shaft carried by said boom, and a flexible driving element connecting said shafts, of means associated with said element and coacting therewith to compensate for changes in the relative positions of said shafts upon said movement of the boom whereby the tension in said element is maintained substantially constant throughout the range of operation of the boom, said means including a member pivotally connected to said boom, and a second member relatively fixed with respect to said frame, one of said members being provided with a groove, the other of said members being adapted and arranged to traverse said groove whereby said first member is caused to change its angular relation with respect to said boom upon said pivotal movement of the latter.

3. In a machine of the character described, the combination with a supporting frame, a driving shaft rotatably mounted on said frame, a boom connected to said frame for pivotal movement about an axis eccentric to the axis of rotation of said shaft, a shaft carried by said boom, and a flexible driving element connecting said shafts, of rotary means engaging said element, a member supporting said means for pivotal movement about an axis relatively fixed with respect to said boom, and a second member fixed relatively with respect to said frame and coacting with said first-named member to cause said movement of said means upon pivotal movement of said boom whereby said means acts to maintain the tension of said element substantially constant throughout the range of movement of the boom.

4. In a machine of the character described, the combination with a supporting frame, a driving shaft rotatably mounted on said frame, a boom connected to said frame for pivotal movement about an axis eccentric to the axis of rotation of said shaft, a shaft carried by said boom, and an endless drive chain connecting said shafts, of a pair of members arranged on opposite sides of said boom and connected to the latter for pivotal movement with respect thereto about an axis relatively fixed with respect to the same, said members being provided with grooves, a pair of sprocket wheels arranged between said members and rotatably supported thereby, said wheels engaging the respective runs of said chain, and elements fixed relatively with respect to said frame and adapted and arranged to traverse said grooves whereby said members are caused to change their angular rela-

tion with respect to said boom in such wise as to cause said sprocket wheels to maintain the tension of said chain substantially constant for all positions of the boom throughout the range of movement thereof.

5. In a power shovel, the combination with a supporting frame, a boom pivotally connected to said frame, a shaft carried by said boom, a driving shaft rotatably mounted on said frame, and an endless chain connecting said shafts, chain take-up means comprising a member pivotally connected to said boom, and a second member fixed relatively with respect to said frame and engaging said first member to cause pivotal movement thereof with respect to said boom upon angular adjustment of the latter with respect to said frame, said first member engaging said chain.

6. The combination with the boom and crowding chain of a power shovel, of means associated therewith for automatically regulating the tension of said chain upon adjustment of the boom, said means including a member pivoted to the boom and engaging said chain, and means for guiding said member in its movement incident to adjustment of the boom.

7. The combination with the boom and crowding chain of a power shovel, of means associated therewith for automatically regulating the tension of said chain upon adjustment of the boom, said means including a member pivoted to the boom and engaging said chain, and means for supporting and guiding the free end of said member to confine and control the movements thereof occasioned by adjustment of the boom.

8. The combination with the boom and crowding chain of a power shovel, of means associated therewith for automatically regulating the tension of said chain upon adjustment of the boom, said means including a member pivoted to the boom and engaging said chain.

9. The combination with the boom and crowding chain of a power shovel, of means associated therewith for automatically regulating the tension of said chain upon adjustment of the boom, said means including a member pivoted to the boom and engaging downwardly upon both runs of said chain.

10. The combination with the boom and crowding chain of a power shovel, of means associated therewith for automatically regulating the tension of said chain upon adjustment of the boom, said means including arms pivoted to opposite sides of said boom and extending rearwardly therefrom on both sides of said chain, a plurality of pins extending between said arms, and sprocket wheels mounted on said pins and engaging both runs of said chain.

11. The combination with the boom and crowding chain of a power shovel, of means associated therewith for automatically regu-

- lating the tension of said chain upon adjustment of the boom, said means including arms pivoted to opposite sides of said boom, a plurality of pins extending between said arms, 5 sprocket wheels mounted on said pins and engaging both runs of said chain, and means engaging one of said arms for controlling the movements of said sprocket wheels upon adjustment of the boom.
- 10 12. The combination with the boom and crowding chain of a power shovel, of means associated therewith for automatically regulating the tension of said chain upon adjustment of the boom, said means including arms 15 pivoted to opposite sides of said boom and extending rearwardly therefrom on both sides of said chain, a plurality of pins extending between said arms, and sprocket wheels mounted on said pins and engaging both runs 20 of said chain, said arms having arcuate grooves formed therein, and fixed elements engaged within said grooves for confining and controlling the movement of said arms upon adjustment of said boom.
- 25 13. In an excavating machine of the class described, the combination of a supporting frame, a boom pivotally mounted on the frame, a driving element on the frame, a driven element on the boom, the arrangement being such that the distance between the elements is varied by pivotal movement of the boom, a flexible connector associated with the driving element and the driven element, an equalizing device adapted 30 for movement with respect to the boom and the frame for varying the path of travel of the flexible connector and means for positively actuating said equalizing device to compensate for the varying distance between the 35 driving and driven elements upon pivotal movement of the boom so as to maintain the length of the path of travel of the flexible connector constant.
- 40 14. In an excavating machine of the class described, the combination of a supporting frame, a boom, a pivot for securing one end of the boom to the frame, a driving shaft and a sprocket wheel on the frame, a driven shaft and sprocket wheel on the boom, the arrangement being such that the distance between 45 shafts is varied by pivotal movement of the boom, a sprocket chain connecting the sprocket wheel on the boom to the sprocket wheel on the frame, the path of travel of 50 said chain being in a single plane and means in said plane actuated by the boom for preventing slack in the chain when the boom is rotated about its pivot.
- 55 15. In an excavating machine of the class described, a frame, a boom pivoted to the frame, a shaft on the boom, a shaft on the frame, a continuous flexible connector associated with said shafts for conveying torque from one to the other, the path of travel of 60 said flexible connector being in the plane of 65 the path of travel of said boom about its pivot and means actuated by said boom for preventing slack occurring in said flexible connector when the distance between the shafts is varied by movement of the boom 70 about its pivot.
- 75 16. In an excavating machine of the class described having a frame and a boom pivoted thereto, two shafts adapted to rotate about parallel axes, one shaft being mounted on the frame and the other on the boom, a flexible connector for conveying torque from one shaft to the other and adapted to travel in such a way that it remains in a given plane, the arrangement being such that the 80 distance between the axes of the shafts is varied by pivotal movement of the boom, equalizing means for maintaining the length of the path of travel of a point on the connector constant and means for automatically and positively actuating said equalizing means to compensate for the variations in the distance between the axes of the shafts caused by pivotal movement of the boom over 85 its entire range of movement.
- 90 17. In an excavating machine of the class described having a frame and a boom pivoted thereto, two shafts adapted to rotate about parallel axes, one shaft being mounted on the frame and the other on the boom, a sprocket 95 chain for conveying torque from a sprocket wheel on one shaft to a sprocket wheel on the other, the arrangement being such that the distance between the axes of the shafts is varied by pivotal movement of the boom and 100 equalizing means for preventing slack in the chain when the boom is moved about its pivot, said equalizing means consisting of a carrier actuated by the boom, means for constraining the movement of the carrier to a 105 definite predetermined path and guides carried by the carrier for engaging both runs of the chain.
- 110 In witness whereof we hereto affix our signatures.
